DISPENSING CONTAINER OR SIMILAR ARTICLE

Wayne F. Robb, Denver, Colo., assignor to Shaw
Insulator Company, Irvington, N. J., a corporation of New Jersey

Application July 30, 1948, Serial No. 147,946

Term of patent 3½ years

(Cl. D52—2)

To all whom it may concern:

Be it known that I, Wayne F. Robb, a citizen of the United States, residing in Denver, in the county of Denver and State of Colorado, have invented a new, original and ornamental Design for a Dispensing Container or Similar Article, of which the following is a specification, reference being had to the accompanying drawing, forming part thereof:

Fig. 1 is a front elevation of a dispensing container showing my new design.

Fig. 2 is a side elevation of the container.

Fig. 3 is a rear elevation of the container.

Fig. 4 is a bottom plan view of the container.

Fig. 5 is a top view of the container.

I claim:

The ornamental design for a dispensing container or similar article, substantially as shown.

WAYNE F. ROBB.
